MANUALLY OPERATED MEANS FOR
PROPELLING BOATS

Claus H. Swenson, Minneapolis, Minn.

Application January 3, 1949, Serial No. 68,937

11 Claims. (Cl. 115—31)

1

My invention relates to improvements in boat propulsion and more particularly to propellers actuated by manually operated pedals.

The object of this invention is to provide novel propellers, pedals and operating connections from the pedals to the propellers.

To the above end the invention consists of the novel devices and combination of devices herein-after described and defined in the claims.

In the accompanying drawings, which illustrate the invention, like characters indicate like parts throughout the several views.

Referring to the drawings:

Fig. 1 is a perspective view of a row boat having the invention embodied therein;

Fig. 2 is a fragmentary view partly in elevation and partly in section taken on the line 2—2 of Fig. 1, on an enlarged scale;

Fig. 3 is a fragmentary detail view principally in section taken on the line 3—3 of Fig. 2, and also showing by means of broken lines, a foot applied to the rocking plate on one of the pedals;

Fig. 4 is a fragmentary view partly in plan and partly in section taken on the line 4—4 of Fig. 1, on the same scale as Fig. 2;

Fig. 5 is a view principally in elevation with some parts sectioned on the line 5—5 of Fig. 4;

Fig. 6 is a side elevation view of the propeller shown in Fig. 4;

Fig. 7 is a fragmentary detail view principally in section, taken on the line 7—7 of Fig. 4, on an enlarged scale;

Fig. 8 is a detail view with some parts sectioned on the line 8—8 of Fig. 1, on the same scale as Fig. 7;

Fig. 9 is an outside elevational view of the parts shown in Fig. 8; and

Fig. 10 is a fragmentary plan view of the parts shown in Fig. 9.

The invention is shown embodied in a row boat, indicated as an entirety by the numeral 11, with the exception of the center bow facing seat 12 and the gunwales 13.

The numeral 14 indicates a pair of propellers for propelling the boat 11, and the numeral 15 indicates a pair of pedals for independently operating said propellers. The propellers 14, the pedals 15, and the parts associated therewith are identical therewith the one with the other with the exception that they are rights and lefts.

The pedals 15 are located between the seat 12 and the bow of the boat 11 and each thereof is a vertically disposed, relatively U-shaped member, the upper ends of which are connected by a cross-tie rod 16 on which is mounted a tubu-

2

lar hand-hold 17. Each pedal 15, at its intermediate portion, is secured by bearings 18 to the inner end portion of a long sleeve 19 that extends transversely under said pedal. This sleeve 19 is turnably mounted on a fixed rod 20 that extends across the boat 11, and is mounted at its end portions, in bearings 21 secured to the gunwales 13.

On the outer end portion of each sleeve 19 is an upstanding crank-arm 22 having on its upper end portion an out-turned crank-pin 23 that is parallel to said sleeve. Each pedal 15 is provided with a rocking foot plate 24 having at its longitudinal center, a transverse rod 25 to which it is rigidly secured. This rod 25, at its end portions, is journaled in bearings 26 on the pedal 15. The foot plate 24 fills the space in the pedal 15 below its sleeve 19 except for a working clearance. Each pedal 15 is yieldingly held retracted by a pair of coiled springs 27 anchored at one of their ends to an eye 28 on the inner side of the respective gunwale 13. These springs 27 are in diverging relation from the eye 28 and are attached at their other end to eyes 29 secured to the pedal 15, the one above and the other below the rod 25.

The foot on the foot plate 24, shown by broken lines in Fig. 3, is designated by the letter 'a.'

Each propeller 14 comprises a pair of duplicate flat rectangular blades 30 connected by a hinge 31 for opening and closing movement in substantially a horizontal plane. These blades 30, when in operative or propelling positions, are in rearwardly diverging relation and are folded, the one upon the other, when in inoperative positions, and being drawn through the water by the forward movement of the boat 11. The propellers 14 are connected to the crank-pins 22 by a pair of long tubular guide rods 32. These guide rods 32, at their forward ends, terminate in bifurcated loop-like bearings 33 in which the crank-pins 22 are turnably mounted and have a limited relatively circumferential movement. Nuts 34 applied to the outer end portions of the crank-pins 22 hold the bearings 33 thereon. A pair of rearwardly projecting upper and lower bearing arms 35 are rigidly secured to the rear end portion of each guide rod 32. These bearing arms 35 diverge from the guide rod 32 and their free end portions are parallel, and the end portions of the pintle 36 of the hinge 31 are journaled therein and support the propeller therefrom. This pintle 36, as shown, is in the form of a nut-equipped bolt.

Rigidly secured to the propeller blades 30, at their vertical centers and outer faces, is a pair

of forwardly projecting crank arms 37 in crossed arrangement, and their free end portions are in the form of hooks 38. In each tubular guide rod 32 is a pair of small control rods 39 having on their forward ends eyes 40, through which the respective crank-pin 22 projects. On the rear ends of the control rods 39 are eyes 41 with which the hooks 38 on the crank-arms 37 interlock. The guide rods 32 at their intermediate portions, slidably rest on concave guide rollers 42 journaled in U-shaped brackets 43. The brackets 43 have on the upper ends of their inner side members hooks 44 that extend transversely over the gunwales 13 and downwardly on the inside thereof. Lock screws 45 have threaded engagement with the hooks 44, impinging the inner sides of the gunwales 13 and rigidly secure the brackets 43 thereto.

Each guide rod 32 is held on its guide roller 42 by a similar concave roller 46 journaled in a pair of rearwardly projecting arms 47 rigidly secured to a transverse pin 48 journaled in the side members of the bracket 43. A coiled spring 49 is attached to the outermost arm 47 and anchored therebelow to the bracket 43, as indicated at 50. Obviously, the springs 49 yieldingly hold the rollers 46 pressed onto the guide rod 32, and in turn hold said guide rods on the guide rollers 42.

The rollers 46, which are yieldingly held for swinging movement, in addition to holding the guide rods 32 on the rollers 42 perform another important function in which they act as brakes to retard endwise movements of the guide rods 32 so that they will not interfere with the control rods 39 in the act of operating the propeller blades 30.

As heretofore stated, the springs 27 yieldingly hold the foot-plate-equipped end portions of the pedals 15 retracted. An operator on the seat 12 with his feet on the foot plates 24 imparts forward movement to the boat 11 by pressing forwardly on said foot plates, turning the foot pedals 15 and the sleeves 19, to which they are attached, about the axis of the rod 20. This turning movement of the sleeves 19 swings the crank arms 22 rearwardly, and the initial movement thereof moves the crank pins 23 in the loop-like bearings 33 which imparts rearward endwise movement to the rods 39 and said rods, in turn, acting on the crank arms 37, opens the propeller blades 30. Further rearward movement of the crank-arms 22 brings the crank-pins 23 into engagement with the front ends of the guide rods 32, which at this time are held by the resistance of the water on the open blades 30. With the crank pins 23 held by the guide rods 32, as a base of resistance, force applied to the pedals 15 by the operator will cause the crank-arms 22 to swing about the axis of the crank-pins 23 and thereby move the boat 11 forwardly in the water. When the operator releases pressure on the pedals 15, the tensioned spring 27 will retract said pedals and thus swing the crank-arms 22 forwardly and also move the crank-pins 23 in the bearings 33. This movement of the crank-pins 23 in the bearings 33 will pull the control rods 39 forwardly and thus operate the crank-arms 37 to close the blades 30 so that they will be moved forwardly in the water with very little resistance. The rear end portions of the control rods 39 will freely bend during opening and closing of the blades 30.

If desired, the pedals may be operated by arm movement simply by grasping the hand-holds 17. The rocking foot plates 25 permit the pedals

15 to be operated without the strain of ankle movement.

From what has been said, it will be understood that the invention described is capable of modifications as to details of construction and arrangement within the scope of the invention herein disclosed and claimed.

What I claim is:

1. In a device of the class described, a support, a pair of U-shaped pedals the side members of which are intermediately pivoted on the supports, each pedal having a crank-arm operatively connected therewith, a pair of propellers, connections from the crank arms to the propellers, a rocking foot plate mounted in each pedal between its transverse member and said support, and a hand-hold on the upper end portions of said side members of the pedals.

2. In a device of the class described, a transverse shaft having bearings at its ends, a pair of turnable sleeves on the shaft, a vertically disposed U-shaped pedal secured to the inner end portion of each sleeve, a foot plate on each pedal between its transverse member and the shaft and intermediately pivoted to the side members of the pedals, a crank-arm on the outer end of each sleeve, a pair of propellers, and connections from the crank-arms to the propellers.

3. The structure defined in claim 2 in which the side members of the pedals are intermediately secured to the sleeves, and further including a hand-hold on the upper end portion of the pedals.

4. In a device of the class described, a transverse shaft having at its ends bearings applicable to a boat, a pair of turnable sleeves on the shaft, a vertically disposed U-shaped pedal intermediately secured to the inner end portion of each sleeve, a foot plate in each pedal between its transverse member and the shaft, and intermediately pivoted to the side members of the pedal, a cross-tie pin connecting said side members at their upper end portions, turnable tubular hand-holds on said pin, a crank-arm on the outer end of each sleeve, a pair of propellers, and connections from the crank-arms to the propellers.

5. The structure defined in claim 4, further including yielding means applicable to the boat as an anchor, attached to each pedal and under strain to retract the same.

6. In a device of the class described, a transverse shaft having at its ends bearings applicable to a boat, a pair of turnable sleeves on the shaft, a vertically disposed U-shaped pedal intermediately secured to the inner end portion of each sleeve, a foot plate in each pedal between its transverse member and the shaft and intermediately pivoted to the side members of the pedal, a cross-tie pin connecting said side members at their upper end portions, a tubular hand-hold on the pin, a spring for retracting each pedal and having at one end means for anchoring the same to said boat, the other end of the spring being attached to the outer side member of the respective pedal, a crank-arm on the outer end of each sleeve, a pair of propellers, and connections from the crank-arm to the propellers.

7. In a device of the class described, a pair of crank-arms applicable to a boat, and means operatively connected to each crank-arm for independently operating the same, a pair of tubular guide rods attached at one of their ends to the crank-arms, a pair of propulsion blades attached to each guide rod, control rods in the guide rods for actuating the propulsion blades from the

crank-arms, and a pair of brackets applicable to the sides of the boat and having rollers on which the guide rods are intermediately supported.

8. The structure defined in claim 7, further including yielding means anchored to the brackets and holding the guide rods on the rollers.

9. The structure defined in claim 7, further including pressure rollers attached to the brackets for vertical swinging movement, and springs anchored to the brackets and yieldingly holding the pressure rollers on the guide rods in offset positions relative to the first noted rollers.

10. In a device of the class described, a pair of crank-arms, means attached to each crank-arm for independently operating the same, said crank-arms having on their outer ends crank pins, a pair of rearwardly projecting tubular guide rods, said guide rods having in their front end portions longitudinal slots through which the crank pins project, a propeller comprising a pair of hingedly connected blades pivoted to the rear end portion of each guide rod, and connections in the guide rods actuated by the crank pins for opening and closing the propeller blades.

11. In a device of the class described, a pair of crank-arms, means attached to each crank-arm for independently operating the same, said crank-arms having on their outer ends crank pins, a pair of rearwardly projecting tubular

guide rods, said guide rods having in their front end portions longitudinal slots through which the crank pins project, a propeller comprising a pair of hingedly connected blades pivoted to the rear end portion of each guide rod, a pair of forwardly projecting crank-arms in crossed arrangement on the blades of each propeller, and a pair of control rods in each tubular guide rod attached at their front ends to the crank pin and at their rear ends to the crank arms.
